Francesco Collura, New York, N. Y., assignor to The Roberk Company, Norwalk, Conn., a corporation of Connecticut

Application February 14, 1956, Serial No. 40,168

Term of patent 7 years

(Cl. D14—6)

Figure 1 is a side elevational view of a rearview mirror, showing my new design, with the mounting arm and mirror shown in dotted lines.

Fig. 2 is a top elevational view of the mounting base.

Fig. 3 is a rear view of the mounting base.

Fig. 4 is a front view of the mounting base.

The dominant features of my design reside in the portions shown in full lines.

I claim:

The ornamental design for a rearview mirror, as shown and described.
